**SPIRAL BIMETAL OPERATED COOLANT
LEVEL SWITCH**

Marvin T. Carlson, Anderson, Ind., assignor to General
Motors Corporation, Detroit, Mich., a corporation of
Delaware

Filed Jan. 26, 1965, Ser. No. 428,121
7 Claims. (Cl. 200—113)

This invention relates to electrical switches and more particularly to a spiral, bimetal operated, coolant level switch.

It is an object of the present invention to provide an improved fluid level switch that utilizes a heated bimetal immersed in the fluid whose level is to be monitored.

It is another object of the present invention to provide an improved fluid level switch wherein a spiral-shaped bimetal is utilized to provide the movement of a contact member during a switching action.

It is still another object of the present invention to provide an improved electrical switch that is responsive to the temperature of a coolant in an engine cooling system to provide a visual indication for a vehicle operator of a low coolant level.

Further objects and advantages of the present invention will be apparent from the following description, reference being had to the accompanying drawings wherein a preferred embodiment of the present invention is clearly shown.

In the drawings:

FIGURE 1 is a diagrammatic illustration of the electrical circuit in which the subject invention is used, the invention being shown in an operative environment;

FIGURE 2 is a plan view of the subject invention, illustrated with parts broken away, thereby exposing the interior portion of the subject device;

FIGURE 3 is a sectional view of the subject invention taken along line 3—3 of FIGURE 2;

FIGURE 4 is a sectional view of the subject invention taken along line 4—4 of FIGURE 2.

Referring now to FIGURE 1, a switch body, generally designated by the numeral 10, is illustrated in a typical mounting position on an automobile vehicle engine wherein a portion of the switch extends into the cooling system of the engine. A battery 12 has one terminal grounded and another terminal conductively engaging a terminal 14 of the switch 10 through an ignition switch 16. A terminal 18 of the switch 10 grounds an indicating lamp 20 through the switch body. It is understood that the switch body 10 is grounded to the vehicle engine.

Referring now to FIGURE 3, the terminal 14 is illustrated as being carried by a non-conductive portion 22 of the switch body 10. The portion 22 is formed integrally with the base of the switch and is composed of any well-known insulating material. A conductive rivet 24 firmly holds the terminal 14 engaged with the portion 22 and engages a conductive strip 26 on an opposite end. The conductive strip 26 furnishes a conductive path between the rivet 24 and a spiral-shaped bimetallic element 28. In FIGURE 3 it is seen that the bimetallic element 28 is suspended below the level of a fluid 30 carried in a fluid passage 32 of the vehicle engine.

Referring to FIGURE 4, the bimetallic element 28 is carried by a conductive post 34 which is secured to

2

the bimetallic element at 36 so as to be non-rotatable with respect thereto. The conductive post 34 has a diameter 37 carried in an aperture 38 in the non-conductive portion 22 of the switch body 10. A diameter 40 of the conductive post 34 is carried in an aperture 42 in the portion 22 of the switch body 10. It is clear that the side of the aperture 42 provides a bearing surface for the conductive post 34 as it rotates during a switching action to be hereinafter described. A smaller diameter pocket 44, formed at the base of the aperture 42, is arranged to receive a sealing O-ring 46. The O-ring 46 is composed of any well-known elastomeric material and serves the dual purpose of providing a seat for the flat portion 48 of the post 34 disposed between the diameter 40 and the diameter 37 as well as sealing the compartment 50 from the fluid 30 in the cooling passage 32.

A resilient conductive member 52 is arranged to rotate with the conductive post 34, being secured thereto, and includes outwardly projecting resilient legs 54 and 56. The leg 54 is adapted to maintain contact with a conductive wall 58 of the switch body 10 while the leg 56 is adapted to slide on the conductive wall 58 and selectively engage a contact rivet 60 which in turn conductively engages the terminal 18. It should be noted that the contact rivet 60 is mounted in an insulated manner with respect to the conductive wall 58 by being enclosed in a plug 62 formed of any well-known insulating material. The terminal 18 is insulatedly mounted with respect to the wall 58 by the insulating washer 64 disposed between the terminal 18 and the wall 58. The conductive post 34 is piloted at its upper end by a portion 66 cooperating with a pocket 68 formed in the wall 58.

Referring to FIGURE 3, the switch body 10 is secured to a wall of the cooling passage 32 by means of bolts 70 compressing a gasket 72 between portions of the wall 58 and a wall 74 of the cooling passage 32.

Referring to FIGURE 2, the resilient conductive member 52 is illustrated as being connected to the conductive post 34. The leg 54 of the member 52 is limited in its movement in one direction by an outwardly projecting flange 76 integrally formed with the wall 58. When the leg 54 is moved in a counterclockwise direction, as viewed in FIGURE 2, to a point where it engages the rivet 60, the leg 54 will simultaneously engage the flange 76 to prevent any further movement thereof.

In operation, the ignition switch 16, illustrated in FIGURE 1, is closed and power is thereby provided to the terminal 14 and to the lamp 20. Referring to FIGURE 3, the power to terminal 14 is conducted through the rivet 24, through the strip 26, to the bimetal 28, and on through the conductive post 34, to the leg 54, to ground, as seen in FIGURE 3. The power thus provided heats the bimetallic element 28 and causes it to have a tendency to rotate on the axis of the post 34, the opposite end of the bimetallic element being held stationary by engagement with the conductive strip 26. Under normal operating conditions, when there is fluid in the passage 32, the tendency of the bimetallic element 28 to rotate along its spiral form is offset by the cooling effect of the fluid 30. During a predetermined acceptable range of fluid temperatures, this cooling effect will continue as long as fluid remains in the passage 32. Under these conditions, the member 52 will be in sub-

stantially the position shown by the solid lines in FIGURE 2. It is seen therein that the member 52 is out of engagement with the rivet 60 and, therefore, no current can flow through the ungrounded lamp 20.

When the temperature of the fluid 30 exceeds certain predetermined limits or the fluid in the passage 32 escapes, leaving the bimetallic element 28 exposed, the tendency of the element 28 to rotate on the axis of the post 34 will be realized, resulting in a movement of the member 52. Referring to FIGURE 4, it is seen that the fluid 30 has receded below the depth to which the bimetallic element 28 is disposed and the leg 56 has moved from the position shown in FIGURE 3 into conductive engagement with the rivet 60. In this situation, a parallel circuit is set up with the bimetallic element 28 still being heated and an alternate path for current flow provided through lamp 20, to the terminal 18, through the member 52 to ground. The lamp 20 is thereby grounded and becomes incandescent, alerting the operator of the vehicle to the fact that the temperature limits established for proper operation of the cooling system have been exceeded and maintenance is necessary. It is understood that the particular temperature ranges established for satisfactory operation of the cooling system are determined by the design, and an appropriately operative bimetallic element 28 can be provided in a given system to bring about the desired result.

The utility of the subject invention is extended due to its responsiveness both to a dropping of fluid level in a fluid chamber below the level of the bimetal as well as being responsive to the total absence of fluid in the chamber. It is clear that the heat developed by the bimetal 28 can be dissipated by the fluid 30 under normal operating conditions, but cannot be satisfactorily dissipated when the fluid level recedes or the fluid temperature exceeds predetermined limits. Therefore, the subject device can be utilized as a level sensing mechanism by suspending the bimetallic element 28 down to a minimum determined level in a fluid container. In this instance, the temperature of the fluid need not be controlling of the action of the bimetal, but the actual presence of the fluid surrounding the bimetal is required in order to gain the required dissipation of heat.

While the embodiment of the present invention as herein disclosed, constitutes a preferred form, it is to be understood that other forms might be adopted.

What is claimed is as follows:

1. A fluid level indicator comprising: a switch body; first terminal means carried through one wall of said switch body and adapted to conductively engage a power source; second terminal means carried in one wall of said switch body and adapted to electrically engage an indicator light, said second terminal means having a conductive portion exposed within said switch body; contact means pivotally supported by said switch body and including two outwardly projecting resilient legs, a first of said legs selectively engaging the exposed portion of the second terminal, a second of said resilient legs being arranged to maintain a conductive relationship between said switch body and a ground; and temperature responsive means carried by said contact means and including a portion in conductive engagement with the first terminal, said temperature responsive means having means arranged to pivot said contact means in response to a raising of temperature of a fluid thereby moving a first of said outwardly projecting legs into conductive engagement with the second terminal providing thereby a ground for the light connected thereto.

2. A fluid level indicator for use with an automobile engine cooling system, said fluid level indicator comprising: a switch body adapted to be mounted over an opening in the engine cooling system; a first terminal adapted to electrically engage a power source and being mounted through one wall of said switch body; a second terminal adapted to conductively engage an indicating device and

being mounted through another wall of said switch body, said second terminal having a conductive portion exposed within said switch body; resilient contact means being pivotally supported by said switch body and including a portion projecting into thermal conductive relationship with fluid in the vehicle cooling system, a portion of said contact means selectively engaging said second terminal and another portion of said contact means being arranged to provide a ground for said first terminal thereby; and temperature responsive means carried by a portion of said contact means in the opening of the engine cooling system wherein a portion of said temperature responsive means is submerged in the fluid therein and responsive to the temperature thereof, said temperature responsive means being heated by power through said first terminal and thereby poised for deflection, said temperature responsive means being normally cooled by the fluid in the engine cooling system thereby preventing any deflection during heating of said temperature responsive means, said temperature responsive means being deflectable as cooling from the fluid in the engine cooling system is lost thereby rotating a portion of said contact means into conductive engagement with the second terminal thereby completing an electrical circuit to the indicating device.

3. A fluid level indicator according to claim 2 wherein the temperature responsive means is a spiral-shaped bimetallic element carried by said contact means.

4. The fluid level indicator according to claim 3 wherein the spiral-shaped bimetallic element is heated and controllably mounted by engaging the first terminal, said spiral-shaped bimetallic element being mounted at its center to said contact means.

5. A fluid level indicator adapted for use with the cooling system of vehicle engines, said indicator comprising: an indicator body adapted to be mounted over an aperture in the engine cooling system; a first terminal adapted to conductively engage a power source and being carried through one wall of said switch body; a second terminal adapted to conductively engage an indicating device and being carried through one wall of the switch body with a conductive portion disposed therein; said first terminal being insulated with respect to said switch body, said switch body being grounded through the vehicle engine; resilient contact means being pivotally supported by a portion of said switch body and including a portion suspended in the engine cooling system to a level normally containing a fluid, said contact means having a resilient outwardly projecting portion selectively engaging the conductive portion of said second terminal and having a second outwardly projecting resilient portion slidably maintaining conductive relationship to the grounded portion of the switch body; and temperature responsive means carried by the portion of the contact means suspended in the engine cooling system and having a second portion conductively engaging said insulated first terminal, power from the power source being supplied to the temperature responsive means through the insulated first terminal to ground, the heat generated thereby being normally dissipated by the fluid in the engine cooling system, said contact means being selectively pivotable into conductive engagement with the second terminal when fluid reaches a level in the engine cooling system wherein the heat is not dissipated from the temperature responsive means, said pivoting contact means energizing a circuit through the temperature responsive means to the indicating device to alert a vehicle driver of a level in the engine cooling system below the suspended disposition of the temperature responsive means.

6. The fluid level indicator according to claim 5 wherein the temperature responsive means is a spiral-shaped bimetallic element held at one end by the conductive engagement with the first terminal and held at an opposite end by the portion of the contact means suspended in the fluid of the engine cooling system, said temperature

responsive means being thereby pivotable on its own axis against the fixed mounting to the first terminal.

7. The fluid level indicator according to claim 6 wherein the contact means is a conductive element pivotally supported in a pocket integrally formed with a wall of said switch body, said integrally formed pocket having a multidiameter inner periphery, a smallest diameter of which is arranged to receive a bearing O-ring and sealing element to support a larger diameter portion of the contact means in a larger diameter portion of said pocket. 10
